FIG. 1 is a top plan view of a reed switch envelope assembly;

FIG. 2 is an end elevational view thereof;

FIG. 3 is a side elevational view thereof;

FIG. 4 is a side elevational view of a modified form of the reed switch envelope assembly described in FIG. 1 showing my new design;

FIG. 5 is an end elevational view thereof;

FIG. 6 is a bottom plan view thereof;

FIG. 7 is a bottom plan view of a modified form of the reed switch envelope assembly described in FIG. 1 showing my new design;

FIG. 8 is a top plan view thereof;

FIG. 9 is an end elevational view thereof;

FIG. 10 is a top plan view of a modified form of the reed switch envelope assembly described in FIG. 1 showing my new design;

FIG. 11 is a bottom plan view thereof;

FIG. 12 is a side elevational view thereof;

FIG. 13 is an end elevational view of a modified form of the reed switch envelope assembly described in FIG. 1 showing my new design;

FIG. 14 is a side elevational view thereof;

FIG. 15 is a top plan view of a modified form of the reed switch envelope assembly described in FIG. 1 showing my new design;

FIG. 16 is a bottom plan view thereof;

FIG. 17 is a top plan view of a modified form of the reed switch envelope assembly described in FIG. 1 showing my new design;

FIG. 18 is an end elevational view thereof;

FIG. 19 is a bottom plan view of a modified form of the reed switch envelope assembly described in FIG. 1 showing my new design;

FIG. 20 is an end elevational view thereof.

The sides opposite to the sides shown in FIGS. 3, 4, 12 and 14 are identical to these respective figures.

The ends opposite to the ends shown in FIGS. 2, 5, 9, 13, 18 and 20 are identical to these respective figures.

The bottom plan views opposite to the top plan view shown in FIGS. 1 and 17 are identical to these respective figures.

The top plan view opposite the bottom plan view of FIG. 6 is the same as that of FIG. 1.

The side elevational views of the modified form of the reed switch envelope assembly described in FIGS. 7, 8, and 9 and the modified form of the reed switch envelope assembly described in FIGS. 19 and 20 are identical to FIG. 4.

The end elevational views of the modified form of the reed switch envelope assembly described in FIGS. 10, 11 and 12 are identical to FIG. 9.

The top plan view and the bottom plan view of the modified form of the reed switch envelope assembly described in FIGS. 13 and 14 are identical to FIG. 10.

The end elevational views of the modified form of the reed switch envelope assembly described in FIGS. 15 and 16 are identical to FIG. 5.

The side elevational views of the modified form of the reed switch envelope assembly described in FIGS. 15 and 16 are identical to FIG. 12.

The side elevational views of the modified form of the reed switch envelope assembly described in FIGS. 17 and 18 are identical to FIG. 3.

The top plan view opposite the bottom plan view of FIG. 19 is the same as FIG. 17.

FIGS. 1, 3, 4, 6, 7, 8, 10, 11, 12, 14, 15, 16 and 18 are broken away to show indefinite length.

I claim:

The ornamental design for a reed switch envelope assembly, as shown and described.
